UNITED STATES PATENT OFFICE.

WILLIAM B. ROBINSON, OF DENVER, COLORADO.

BRICK-SCORING MECHANISM.

1,272,533.

Specification of Letters Patent. Patented July 16, 1918.

Application filed October 9, 1916. Serial No. 124,707.

To all whom it may concern:

Be it known that I, WILLIAM B. ROBINSON, citizen of the United States, residing in the city and county of Denver and State of Colorado, have invented certain new and useful Improvements in Brick-Scoring Mechanisms; and I do declare the following to be a full, clear, and exact description of the invention, such as will enable others skilled in the art to which it appertains to make and use the same, reference being had to the accompanying drawings, and to the characters of reference marked thereon, which form a part of this specification.

15 The present invention relates to improvements in brick making machines and pertains more particularly to marking devices adapted to be located between the feeding machine and the cutter.

20 The invention has for its principal object the provision of suitable marking attachments to be used between the feeding machine and the cutter and adapted to act upon the column of clay as it is moved

25 along on the measuring belt thereby producing designs upon the unfinished material which will appear as irregular scrolls upon two faces of the finished bricks.

A further object of the invention consists 30 in providing marking devices of the kind referred to which will operate automatically and will in no way retard the progress of the brick making machines. The apparatus is capable of various adjustments enabling 35 the operator to control the depth of the imprints or designs to be cut into the brick surfaces.

With these and other objects in view the invention consists in the combination and 40 arrangement of parts more fully set forth in the following specification, illustrated in the accompanying drawing and more particularly pointed out in the appended claim.

In the drawings:—

45 Figure 1 is a front elevation of one embodiment of the present invention, parts being shown in section and taken on the line 1—1 of Fig. 3.

50 Fig. 2 is a side elevation showing the column of clay being fed along the measuring belt and with the marking devices operating thereon.

55 Fig. 3 is a horizontal sectional view taken on the line 2—2 of Fig. 1, looking in the direction of the arrows.

Fig. 4 is a perspective of a single brick

having two of its surfaces marked with the designs such as contemplated by the present invention, and.

Fig. 5 is a fragmental view of a wall constructed of bricks so marked.

Referring now to the drawings, the column of clay is delivered from the feeding machine 5 onto the measuring belt 6 along which it is carried to the cutter (not shown). The marking devices forming the principal features of the present invention are carried on an upright post or standard 7 suitably positioned at one side of the measuring belt 6. As shown clearly in Fig. 1 the column of clay C travels along the measuring belt resting on one of its wider edges. Two marking devices are provided, one operating on the upper edge or surface of the column and the other on the side thereof, consequently when the column is cut into bricks, each individual brick will be marked as shown in Fig. 4 with the design cut on its long narrow surface or edge and also on its small end surface.

The upper marking device is supported on the upright post or standard 7 being suspended from a bracket 8 which is slidably secured to a pair of slotted arms 9 of a supporting bracket 10 fixed to the post 7. Adjusting bolts and nuts 11 are passed through the slotted arms 9 and the corresponding slots 12 formed in the ears 13 of bracket 8 for the purpose of maintaining the bracket 8 in any adjusted position. The bracket plate 8 is provided with a pair of journal boxes 14 between the supporting ears 13, in which is suitably journaled a horizontally disposed driving shaft 15 carrying a pulley 16 at one end thereof which is driven from any suitable power source (not shown) by means of a belt 17. The driving shaft 15 is provided at its opposite end with a pinion 18 keyed thereto and meshing with a gear 19 fixedly carried on the end of a stub shaft 20 supported in a bearing 21 also integral with the bracket plate 8. A pair of vertically spaced bearing arms 22 are formed integral with the bracket plate in the lower of which is slidably mounted a vertical shaft 23 to the lower end of which is secured the marking disk 24 carrying a series of vertically adjustable, depending spikes or markers 25. The upper end of shaft 23 is connected by means of a swivel joint 26 with the lower end of a coaxially disposed shaft 27 threaded into the upper bearing arm 22. A ma-

Manipulating handle wheel 28 threaded on the shaft 27 above its bearing in arm 22 serves to raise and lower the two shafts 27 and 23, together with the marking device 24. The gear 19 is provided at its inner side with a bevel gear 20 formed integral therewith with which meshes with a correspondingly formed bevel gear 30 on the shaft 23 and having a slideable key 31 engaging an elongated keyway 32 in said shaft. It will thus be seen that as the belt 17 drives pulley 16, the pinion 18 rotates driving gear 19 which latter, through its bevel gear 20, drives bevel gear 30 turning shaft 23 and revolving the marking disk 24. The markers 25 are adjusted to approximately the same length and the shaft 23 carrying disk 24 is vertically adjusted by hand wheel 28 to cause the pointed ends of marker 25 to bear into the surface of the clay to the desired depth. As the clay column is moving forwardly in a straight line at right angles to the axis of the marking disk and as the latter is revolved, the pointed markers cut irregular scrolls upon the upper surface of the clay. It will be noted that the axis of the marker disk 24 is slightly out of center with the middle of the clay column.

Below the bracket plate 8 and at the opposite side of the upright 7 a block 33 is secured having transversely journaled therein a driving shaft 34 provided with a pulley 35 at one end and a bevel gear 36 at the other. Power is supplied to the pulley 35 by a belt 37 from a source (not shown). The block 33 has bolted thereto a two armed supporting bracket 38 having spaced bearings 39 in which is journaled a horizontal shaft 40 to the inner end of which is fixed a marking disk 41 smaller than but similar in construction to the disk 24. A bevel gear 42 adapted to mesh with and be driven by the bevel gear 36 is mounted on shaft 40 a sliding key device permitting longitudinal move-

ment between the two. The outer end of shaft 40 which is loosely carried in the bearing 39 is threaded as at 43 and carries thereon a manipulating hand wheel 44. By turning the hand wheel 44 in one direction or the other the shaft 40 may be rotated to move the marking disk 41 toward or away from the side edge of the clay column C, and hence the depth of mark made by the pointed ends of the markers may be varied at will. 55

From the foregoing description the purpose and operation of the marking devices will be apparent. The configurations of the designs may be changed by varying the arrangement of the markers on disks 24 and 41 and the depths of the cuts as previously explained may be regulated by adjusting shafts 23 and 40 through hand wheels 28 and 44 respectively.

Besides producing an artistic and decorative design upon the exposed surfaces of the bricks, the scrolls cut therein aid materially in the rapidity with which they dry out.

Having described my invention what I claim is:

The combination with a brick making machine having a belt adapted to convey a column of clay, a bracket above said belt adjustable laterally of the width of the belt, a vertical spindle mounted in said bracket approximately centrally of the belt, a rotatable scoring device on the lower end of said spindle, and means connected with the upper end of the spindle for vertical adjustment thereof, by which adjustments the design and depth of the scoring may be varied.

In testimony whereof I affix my signature, in presence of two witnesses.

WILLIAM B. ROBINSON.

Witnesses:

C. E. PARSONS,

HELEN A. VILLEMAGNE.
